CLAIM

The ornamental design for a hat, as shown and described.

DESCRIPTION

FIG. 1 is a right side elevational view of a hat showing my new design;

FIG. 2 is a front perspective view which shows the top of the hat;

FIG. 3 is a left side elevational view;

FIG. 4 is a front elevational view;

FIG. 5 is a front perspective view which shows the bottom of the hat; and,

FIG. 6 is a bottom plan view thereof.

The rear elevational view is substantially identical to the front elevational view shown in FIG. 4.
